United States Patent Office.

THEODORE R. TIMBY, OF SARATOGA, NEW YORK.

Letters Patent No. 73,674, dated January 21, 1868.

PAPER-CUTTER.

The Schedule referred to in these Letters Patent and making part of the same.

TO ALL WHOM IT MAY CONCERN:

Be it known that I, THEODORE R. TIMBY, of the town and county of Saratoga, and State of New York, have invented a new and improved Paper-Cutter; and I do hereby declare the following to be a full, clear, and exact description of the same, reference being had to the accompanying drawings, which are made part of this specification.

Figure 1 is a section at $z z$, fig. 3, of a paper-cutter, illustrating my invention.

Figure 2 is an external view of the same.

Figure 3 represents a section thereof in the plane indicated by the line $y y$, fig. 2.

Figure 4 represents a rear edge view, the arrow in fig. 2 indicating the line of vision.

Similar letters of reference indicate corresponding parts in the several views.

My invention is chiefly designed for cutting folded paper, such, for example, as book-leaves, envelopes, sheets of letter-paper, &c.

It consists essentially of a knife pivoted within a case of round, oval, square, oblong, or other form, the said knife being retracted by a spring, and protruded by means of a pin or knob projecting through a slot in the face of the case. The knife when advanced occupies a central position within a slot in the periphery of the case, the sides of which slot guide the paper to the knife, and cause it to cut accurately along the crease.

In the drawings, A represents a flat case of metal, or other material. B is a knife, having a cutting-edge at b. The said knife is mounted on a pivot, C, and provided with a pin or knob, D, which projects through a slot, E, concentric with the pivot C, for the purpose of protruding or thrusting out the knife through a slot, F, in the edge of the case. When in this position, the edge of the knife forms an acute angle with the periphery of the case. A spring, G, retracts the knife within the case when it is released.

The operation is as follows: By applying the thumb to the knob D, the knife is pressed out through the slot F. The paper to be cut is then introduced into the slot in front of the knife, with the latter within the fold of the paper, and, by passing the instrument along the edge of the paper, a smooth and accurate cut is effected with the utmost facility.

My invention provides an instrument of convenient size and shape for carrying in the pocket, and well adapted for opening envelopes, cutting book-leaves, and many other purposes.

The pivot may, if preferred, be located at the lower end or elbow of the knife, or in an intermediate position, and the spring and thumb-knob at the upper end, where the pivot is shown in the drawings. The knife may be thrust out by a spring, and held in by a catch, or the spring may be entirely dispensed with, if preferred.

Having thus described my invention, what I claim as new, and desire to secure by Letters Patent, is—

1. The paper-cutter, so constructed that when the knife is thrust out its cutting-edge will form an acute angle with the edge of the case.

2. The slot F, adapted and employed to guide the paper to the edge of the knife, substantially as set forth.

THEODORE R. TIMBY.
